DESIGN FOR A COMBINED BOOKMARK AND HOLDER CLIP

Raymond F. Brennan, Attleboro, Mass.

Application February 24, 1938, Serial No. 75,375

Term of patent 3½ years

To all whom it may concern:

Be it known that I, Raymond F. Brennan, a citizen of the United States, residing at Attleboro, in the county of Bristol and State of Massachusetts, have invented a new, original, and ornamental Design for a Combined Bookmark and Holder Clip, of which the following is a specification, reference being had to the accompanying drawing, forming part thereof.

Fig. 1 is a perspective view of a combined bookmark and holder clip showing my new design attached to the outline of a book for illustrative purposes,

Fig. 2 is a front elevational view of the holder

clip, showing the bookmark in perspective and illustrating the arrangement of the parts as the bookmark is formed from a suitable strand or ribbon passed through an opening in the holder clip and having means for adjusting its effective length, and

Fig. 3 is a side elevational view of the holder clip showing the bookmark outwardly positioned relative thereto.

I claim:

The ornamental design for a combined bookmark and holder clip, substantially as shown and described.

RAYMOND F. BRENNAN.
